UNITED STATES PATENT OFFICE.

WILLIAM W. TAYLOR, OF NEWARK, NEW JERSEY.

IMPROVED STITCHING-CLAMP.

Specification forming part of Letters Patent No. **59,094**, dated October 23, 1866.

To all whom it may concern:

Be it known that I, WILLIAM W. TAYLOR, of Newark, in the county of Essex and State of New Jersey, have invented a new and useful Improvement in Stitching-Clamps; and I do hereby declare that the following is a full, clear, and exact description thereof, which will enable others skilled in the art to make and use the same, reference being had to the accompanying drawings, forming part of this specification, in which—

Figure 1 is a side view of my improved clamp when open, partly in section, through the line *x x*, Fig. 3. Fig. 2 is a side view of the same when closed, partly in section, through the line *x x*, Fig. 3. Fig. 3 is a horizontal sectional view of the same, taken through the line *y y*, Fig. 2.

Similar letters of reference indicate like parts.

My invention has for its object to furnish an improved stitching-clamp; and it consists in combining a toggle-lever and jointed bars with the jaws of the clamp in such a way that the said jaws may be both opened and closed with the feet of the operator, leaving both his hands free to be used in adjusting the work.

A and B are the jaws of the clamp, which are made of the usual form, and are connected to each other at or near their middle parts by the jointed arms C, as shown in Figs. 1 and 2. The lower end of the jaw or leg B is inserted in the foot-block H, so as to be stationary and support the other parts of the clamp.

The other jaw or leg, A, is a little shorter, its lower end terminating just above the upper surface of the foot-block H.

The lower end of the jaw or leg A is pivoted to the toggle-lever D.

One end of the part *d¹* of the toggle-lever D is pivoted or hinged to the end of the foot-

block H, and the other end of said part is pivoted or hinged to the part *d²* of said toggle-lever D.

The end *d³* of the other part, *d²*, extends beyond the point at which the lower end of the jaw or leg A is pivoted to it, and the end *d⁴* of said part extends beyond the point at which the part *d¹* is pivoted to it, so as to form rests or treadles for the feet of the operator to rest upon in operating the clamp.

The end *h'* of the foot-block H is beveled off, as shown in the drawings, so that the end *d³* of the part *d²* of the toggle-lever D may have space to operate in in opening the jaws of the clamp.

If desired, the jaw or leg B, at or about its middle part, may be attached to a horse, either with or without the lower part of said jaw or leg being cut off, and in this case the outer end of the part *d¹* of the toggle-lever D should be jointed or hinged to the frame of the said horse.

What I claim as new, and desire to secure by Letters Patent, is—

1. The combination of the toggle-lever D with the lower end of the jaw or leg A of the clamp, and with the foot-block H or equivalent, substantially as herein shown and described.

2. The combination of the jointed arms C with the jaws A and B of the clamp, substantially as herein shown and described.

3. An improved stitching-clamp, formed by the combination of the jaws A and B, jointed arms C, toggle-lever D, and foot-block H, or equivalent, substantially as herein shown and described.

WM. W. TAYLOR.
